(57) **CLAIM**

The ornamental design for toy jet, as shown and described.

DESCRIPTION

FIG. 1 is a perspective view of the toy jet in accordance with my new design.

FIG. 2. is a top plan view of the toy jet of FIG. 1.

FIG. 3 is a left-side elevational view of the toy jet.

FIG. 4 is a right-side elevational view of the toy jet.

FIG. 5. is a bottom plan view of the toy jet.

FIG. 6 is a rear elevational view of the toy jet; and,

FIG. 7 is a front elevational view of the toy jet.

The broken lines shown in the figures are for the purpose of illustrating portions of the toy jet and form no part of the claimed design.
